PORTABLE GOLF BALL CLEANER

Louis S. Allen, Alexandria, Va.

Application February 13, 1948, Serial No. 8,119

1. Claim. (Cl. 15—114)

1. This invention relates generally to devices for cleaning golf balls and, more particularly, to such a device which is constructed and adapted to be mounted on a golf club bag whereby it may be carried with the player for use at all times.

Portable ball cleaners of the described type have heretofore been proposed but none of the known devices have proved to be satisfactory and, for that reason, have not been widely used. By this invention, I have provided a ball cleaner which may be easily and quickly mounted on a golf bag or detached therefrom, which is constructed and arranged to be mounted on a golf bag in such a way that the cleaning elements are positioned for quick and efficient use, and which includes a combination of cleaning and scrubbing elements causing quick and thorough cleaning of the ball. In one embodiment of the invention, means are provided for imparting mechanical action to the cleaning and scrubbing elements whereby the advantages of the usual and known fixed-type ball cleaners, which are usually located at the tee, are embodied in a portable ball cleaner. In connection with this embodiment, the invention also provides means for holding the ball fixed while the mechanical cleaning and scrubbing means is moved over it.

Other objects and features of novelty of the invention will be made apparent by the following description and the annexed drawings which, it will be understood, are only illustrative of the invention and impose no limitations thereon not imposed by the appended claims.

Referring to the drawings, in which similar reference numerals refer to like parts,

Fig. 1 is a sectional view, taken on line 1—1 of Fig. 2, of a ball cleaning device according to the invention;

Fig. 2 is a front elevational view of the ball cleaning device shown in section in Fig. 1;

Fig. 3 shows a golf ball cleaning device according to the invention mounted on a golf bag; and

Fig. 4 is an elevational view of the device for attaching the cleaner to a bag.

The preferred form of my invention disclosed in Figs. 1 to 4 comprises a body part 2 which has a semi-circular end 4 and a straight or flat end 6. A circular recess 8 is formed within this body and opens outwardly through one wall thereof. This recess is somewhat larger in diameter than a usual golf ball and may have a depth approximately equal to the radius of such a ball. Within this recess and extending radially into it from the surrounding wall are a plurality of flexible, stiff scrubbing elements 10 which pref-

erably take the form of rubber cylinders or truncated cones. These are preferably formed in circumferential rows, three such rows being disclosed in the drawings. In a preferred form of the invention the elements 10 of each circumferential row are of the same height and are of less height than the next inward row. Because of this construction, the scrubbing surface formed by the protuberances 10 is part-spherical in shape and therefore closely approximates the outer surface of the golf ball. In order to perform the scrubbing operation efficiently, the surface presented by the elements 10 is of such size that when a golf ball is pressed into the recess 8, the scrubbing elements 10 will be compressed and deformed and will therefore exert pressure against the surface of the ball. As clearly illustrated in the drawings, all of the scrubbing elements 10 may be formed on a flat sheet of rubber 12 which may be inserted, in the shape of a cylinder, into the opening 8 where it will closely fit the cylindrical surface 14 of the surrounding and enclosing wall. An inturned lip or flange 16 may be formed on the casing 2 and will overlie the edge of the rubber sheet 12 when the same is in position in the opening. It will be apparent that the scrubbing elements may be formed of a material other than rubber and, if desired, may be bristles.

Within the recess 8 and associated with the scrubbing elements 10 is a cleaning element 20 which, in the preferred form of the invention, is a sponge. This sponge preferably has the same shape as the recess 8 and is of such size that it substantially covers the bottom of the recess, 30 with its peripheral portion 22 under the last row 10c of scrubbing elements, whereby the sponge will be firmly held in place. The sponge is of such thickness that when the golf ball is pressed into the recess 8, the sponge will be compressed, 35 thereby releasing to the surface of the golf ball any water or cleaning fluid which may be held by the sponge. In a preferred form of the invention the sponge 20 is impregnated with a dry detergent material which is made active by the addition of water. This impregnation may be effected, before assembly of the sponge with other parts of the ball cleaner, by soaking the sponge in a detergent liquid and then baking until the sponge is dry, leaving the detergent material in 40 the sponge.

As stated, the surface 6 of the casing or body member 2 is flat and on this flat surface there is positioned and attached, as by screws 26, a plate 28 which is preferably co-extensive with the surface 6. Cleaning or polishing members 30, which

may be bristles, are attached to plate 28 and extend outwardly therefrom, providing means whereby the ball may be polished. Obviously, the polishing members 30 may be attached directly to the casing 2 over the surface 6, thereby eliminating the extra plate 28.

Means are provided by the invention for tightly, resiliently and releasably attaching the ball cleaning device to the upper edge of the wall of a golf bag 40. Such means comprise a spring metal clip member 46 having one extremity positioned between the plate 28 and body 2 and the opposed extremity thereof being free and normally in resilient contact with the rear face 48 of the body member. A handle and operating member 50 is pivotally attached to the lower end of clip 46 and may be moved to a position in which the upper end thereof extends above the clip 46, whereby the operating member may be employed to force the lower end of the clip away from the rear face of the body to permit the upper edge of the wall of a golf bag to be inserted between such face and the clip, after which the arm will tightly and resiliently hold the cleaner to the golf bag. After the cleaning device has been positioned in this manner the handle 50 may be turned down inwardly within the golf bag. When the cleaning device is in the described position on a golf bag, the opening of recess 8 will face outwardly and the polishing elements 30 will face upwardly, thus providing a convenient means for scrubbing, cleaning and polishing the golf ball. This will be done by pressing the ball into the recess 8 and moving and rotating the ball against the scrubbing elements 10 and the sponge 29 until it is cleaned. The bristles 30 may be used as supplemental or separate means for polishing the ball.

While I have described and illustrated a preferred embodiment of my invention, it will be apparent to those skilled in the art that other embodiments, as well as modifications of that disclosed, may be made without departing in any way from the spirit or scope of the invention, for the limits of which reference must be made to the appended claim.

What is claimed is:

A portable golf ball cleaning device comprising, a body member formed of a plurality of sections, one of said sections having a circular recess therein opening outwardly to provide a circular opening in one side wall of said body member, the opposed side wall of said body member providing

a bottom for said recess, a plurality of flexible stiff interior scrubbing members extending radially into said recess from the surrounding cylindrical side wall of said recess and being of increasing length from the opening of said recess inwardly, the said interior scrubbing members being composed of rubber protuberances formed integrally with a flat rubber sheet which lines the cylindrical side wall of said recess, a detergent impregnated sponge member within said recess having its peripheral edge in contact with and held between the innermost interior scrubbing members and the bottom wall of said recess whereby to retain said sponge member at the bottom of said recess, the said interior scrubbing members being of such radial extent and the said sponge being of such thickness that both are compressed and deformed by a golf ball pressed into said recess whereby the surface of the ball when rotated in said recess may be scrubbed and cleaned, another of said body member sections being removably secured to said one body member section, a spring clip means for attaching the device to a golf bag or the like, the said spring clip attaching means having opposed extremities, one of said extremities being frictionally held between said one and another body member sections and the other of said extremities being free and normally in contact with an exterior side wall portion of said body member, and exterior scrubbing members carried on an outer surface of said another body member section for alternative use with said interior scrubbing members.

LOUIS S. ALLEN.
